(57) **CLAIM**

I claim the ornamental design for a release paper for wound treatment devices, as shown and described.

DESCRIPTION

FIG. 1 is a perspective plan view of an ornamental release paper for wound treatment devices in accordance with the present invention showing my new design;

FIG. 2 is an alternate perspective plan thereof;

FIG. 3 is an underside plan view of FIG. 1;

FIG. 4 is a top plan view of FIG. 1;

FIG. 5 is a front elevation of FIG. 1;

FIG. 6 is a rear elevation of FIG. 1;

FIG. 7 is a left side elevation of FIG. 1; and,

FIG. 8 is a right side elevation of FIG. 1.

In the drawings, the broken lines show portions of a release paper for wound treatment devices that form no part of the claim.
